United States Patent Office

Des. 222,466
Patented Oct. 26, 1971

222,466

TOILET SEAT

Hugo Magi, Etobicoke, Ontario, Canada, assignor to
Aqua-Marine Mfg., Limited, Toronto, Ontario, Canada

Filed Apr. 8, 1970, Ser. No. 22,312

Term of patent 3½ years

Int. Cl. D23—02

U.S. Cl. D23—71

FIG. 1

FIG. 2

FIG. 4

FIG. 3

FIG. 1 is a perspective view of a toilet seat embodying my new design;

FIG. 2 is a cross-sectional view taken on line 2—2 of FIG. 1;

FIG. 3 is a top plan view thereof; and

FIG. 4 is a side elevational view thereof.

I claim:

The ornamental design for a toilet seat, as shown.
